UNITED STATES PATENT OFFICE.

JOHN S. BOYD, OF BALTIMORE, MARYLAND.

BAG.

SPECIFICATION forming part of Letters Patent No. 374,037, dated November 29, 1887.

Application filed April 11, 1887. Serial No. 234,377. (No model.)

To all whom it may concern:

Be it known that I, JOHN S. BOYD, a citizen of the United States, residing at Baltimore, in the State of Maryland, have invented certain new and useful Improvements in Bags, of which the following is a specification, reference being had therein to the accompanying drawings.

This invention relates to certain new and useful improvements in bags; and it is especially designed as an improvement on the bags which are ordinarily used for the purpose of shipping flour from the millers to the trade generally.

When flour packed in bags arrives at the house of the commission merchant, it is customary to inspect it, and the employé is supposed to cut the cord which unites the two walls of the bag together and insert the gouge or tool they use in inspecting the flour, draw out a sample, and then proceed to the next bag, where the operation is repeated. In practice, however, instead of doing this, which is more or less slow, they take a knife with them and cut a gash in the side of the bag or punch a hole in the sack with the gouge, which they then insert and obtain their sample, and then go to the next bag, where they repeat the same operation. The cut in the bag, it is needless to say, considerably impairs its value; but it can be readily understood that where there are one thousand or more bags to inspect, the labor of carefully opening and resewing each one is considerable and consumes a great deal of time.

The design of my invention is to make a bag having an aperture on one side covered with a flap, so that the flap can be thrown back and the sample taken through the aperture, which operation can be done rapidly and by unskilled labor, and the inspector can then come along and obtain his sample. This might at first sight seem as slow and tedious as the old way; but, as hereinafter explained, it will be seen that with my improved bag it is quite an improvement on the old method, and at the same time the bag is left in as good condition as it was at first.

In the accompanying drawings, forming a part of this specification, and on which the same letters of reference indicate the same or corresponding features, Figure 1 represents a

side elevation of my improved bag, showing the flap fastened. Fig. 2 is a similar view showing the flap thrown back and a portion of the guard-band broken away, and Fig. 3 is 55 a detail view of my improved buckle.

The letter A designates a bag of the usual or any approved construction and of whatever size or shape may be desired or is customary in the market. To the upper portion thereof 65 and near one side is securely sewed or otherwise fastened a flap, B, terminating at one end in a tongue, C, though not necessarily so, for the flap and tongue may all be of the same size, in which case the buckle is made larger. 65

At the point D, as illustrated in Fig. 2, the bag is provided with an aperture of such size and shape as to easily and readily admit of the entrance of the gouge which the inspector uses, the said aperture being stitched around 70 its edges, so as to prevent fraying; or it may be protected by an eyelet.

The guard-band E is attached to the bag directly on either side of the aperture, and extends across and over the flap B. This band 75 serves two purposes—first, it holds the flap firmly pressed against the aperture, so that the flour will not waste out, and, secondly, it prevents the sides of the flap from sagging, so that nothing will be likely to catch in between 80 the flap and the bag and tear off the former.

The buckle shown in Fig. 3 differs from those ordinarily in use, in the fact that the normal tendency of its tongue is to fly away from its seat, instead of keeping its seat, and 85 is fully described and explained in an application filed by me of even date herewith, Serial No. 234,378, so that I need not further describe it in this place.

Now, we will suppose a bag of flour to have 90 arrived at the commission-house, the same appearing as it does in Fig. 1. The employé goes to the bag and with his right hand pulls back the flap. The tongue of the buckle immediately flies back, and at the same moment 95 that he is pulling back the flap with his right hand he also inserts the index-finger of his left hand between the flap and the bag at the point F, and when the tongue flies back pulls upon the flap and draws it out from under the 100 guard, so that it assumes the position shown in Fig. 2. It will be observed that, owing to

the construction of the buckle, this operation can be done in less than a second. After-
ward the inspector comes along and with his left hand pulls the guard-band E to one side
5 and with his other hand inserts the gouge and obtains his sample of flour, after which he quickly rebuckles the flap, and the bag is intact and ready for reshipment, whereas at present the rents must be sewed up, which 10 operation consumes no little time. It is to be observed that the forward bar, G, of the buckle is depressed, so that when the prong is in operative position the teeth thereof will be in a plane below the surface proper of the buckle 15 and will not be liable to catch in anything.

The buckle may be attached to the bag in any desired manner, and I have shown it held in a loop of cloth which is stitched to the bag.

By my invention the same bag can be used 20 over and over again, whereas, as it is now, the bags being impaired in value by the cut made, are usually sold at reduced rates to grain merchants, who use them for packing feed, &c.

The kind of bag or the shape or size of the 25 flap may be changed at pleasure without departing from the spirit of my invention, the

essential principle of which is the providing the side of the bag with an opening and with an easily-removable flap to cover the said opening.

Having thus fully described my invention, what I claim as new, and desire to secure by Letters Patent, is—

1. The combination, with a bag provided with a mouth and having an inspection-aper- 35 ture, of a flap to cover said aperture and means to secure the flap.

2. The combination, with a bag having a mouth and provided with an inspection-aper- 40 ture, of a cover for said aperture.

3. The combination, with a bag having an aperture in one side thereof, a flap to cover the same, and means to secure the flap, of a guard-band extending over the flap and constructed to hold the same from displacement. 45

In testimony whereof I affix my signature in presence of two witnesses.

JOHN S. BOYD.
